DUPLEX BRAKE CYLINDER

Ellis E. Hewitt, Edgewood, Pa., assignor to The Westinghouse Air Brake Company, Wilmerding, Pa., a corporation of Pennsylvania

Application February 27, 1937, Serial No. 128,086

7 Claims.

(Cl. 309—2)

This invention relates to duplex cylinder mechanisms such for instance as duplex brake cylinder mechanisms for use in fluid pressure brake equipments.

5 The principal object of the invention is to provide an improved duplex cylinder mechanism having two axially aligned cup-shaped pistons adapted to be moved in opposite directions in a cylinder casing having a novel pressure head construction between the pistons to provide a stop for each piston and to also provide a pressure chamber of minimum volume between the pressure sides of the pistons.

10 Other objects and advantages will appear in 15 the following more detailed description of the invention.

In the accompanying drawings, Fig. 1 is a longitudinal sectional view of a duplex cylinder mechanism embodying the invention, and Fig. 2 is an enlarged cross-sectional view of the mechanism taken on the line 2—2 of Fig. 1.

20 As shown, the duplex cylinder mechanism comprises axially aligned oppositely movable cup-shaped pistons 1 and 2 which are slidably mounted in longitudinally aligned cylinder casings 3 and 4, respectively. The adjacent ends of these cylinder casings are integrally connected together by an annular pressure head construction 5 which, as shown in Fig. 1, is V-shaped in cross-section, the walls 6 and 7 of the construction extending inwardly between the pressure faces of the pistons and converging toward each other and constituting stops for the pistons. These walls merge into each other some 25 distance from the longitudinal axis of the cylinders so as to provide an opening 8 of fairly large diameter which constantly connects the pressure chambers 9 and 10 of the cylinders 3 and 4 respectively.

30 Extending between and integral with the walls 6 and 7 are spaced radially arranged longitudinally extending strengthening ribs 11. Also extending between and integral with these walls is a header 12 which extends outwardly into the 35 plane of the outer surface of the cylinder casings, the outer end of the header being provided with end walls 13 and 14. Each end wall is provided with a threaded opening which is in communication with a fluid pressure supply and 40 release passage 15 leading to the opening 8.

45 As shown in Fig. 2, the opening in either one of the header walls is adapted to be either closed by a plug 16 which may be screwed into the wall or to accommodate a supply or release 50 pipe 17 adapted to have screw-threaded con-

nection with the casing. It will here be understood that the plug and pipe 17 are interchangeable so as to accommodate different piping arrangements.

5 Each header end wall is also provided with screw-threaded openings 18 for the reception of bolts when it is desired to secure the supply and release pipe 17 to the header by means of the well known reinforcing pipe flanges, not shown.

10 The pistons may each be of the same construction as those shown in Patent No. 2,055,104, issued September 22, 1936 to William C. Landis and myself. Briefly described, each piston may comprise a cup-shaped piston head 19 having mounted thereon correspondingly shaped 15 packings 20 of the snap-on type having an annular thickened portion 21 which is located near the outer edge portion of the packing. Each piston is provided with a hollow piston rod 22 in which there is pivotally mounted, in the usual 20 manner, a push rod 23 which extends through a central opening in the non-pressure head 24 secured to the cylinder casing. Interposed between and engaging the piston and non-pressure head is the usual release spring 25.

25 Each non-pressure head 24 is provided with the usual breather opening 26 in which there is interposed the usual air strainer 27.

30 When the pistons 1 and 2 are moved to their normal release position as shown in Fig. 1 the thickened portions 21 of the piston packings engage the pressure head of the cylinders and the pistons are brought to a stop by such engagement. Heretofore in duplex cylinder mechanisms the piston rods have been provided with 35 stops which engage with the non-pressure heads of the cylinders to arrest the movement of the pistons in their normal release positions. By utilizing the pressure head construction 5 as a stop for the pistons the non-pressure heads are 40 relieved of this office and as a result such heads may be made lighter than would otherwise be the case.

45 While one illustrative embodiment of the invention has been described in detail, it is not my intention to limit its scope to that embodiment or otherwise than by the terms of the appended claims.

Having now described my invention, what I 50 claim as new and desire to secure by Letters Patent, is:

1. A unitary cylinder casing comprising two longitudinally spaced axially aligned cylinder portions and an annular head V-shaped in cross-

- section and integrally connecting said cylinder portions.
2. A unitary cylinder casing comprising two longitudinally spaced axially aligned cylinder portions and an annular head V-shaped in cross-section and integrally connecting said cylinder portions and defining an always open communication between both of said cylinder portions.
3. A unitary cylinder casing comprising two longitudinally spaced axially aligned cylinder portions, an annular head V-shaped in cross-section and integrally connecting said cylinder portions, and radially arranged longitudinally extending strengthening ribs integral with said cylinder portions.
4. A unitary cylinder casing comprising two longitudinally spaced axially aligned cylinder portions having two integral annular wall portions which extend inwardly toward the longitudinal axis of the cylinder portions and which converge toward each other and merge together about, but spaced away from, the longitudinal axis of the cylinder portions.
5. A unitary cylinder casing comprising two longitudinally spaced axially aligned cylinder portions having two integral annular wall portions which extend inwardly toward the longitudinal axis of the cylinder portions and which converge toward each other and merge together about, but spaced away from, the longitudinal axis of the cylinder portions.
6. A unitary cylinder casing comprising two longitudinally spaced axially aligned cylinder portions having two integral annular wall portions which extend inwardly toward the longitudinal axis of the cylinder portions and which converge toward each other and merge together about, but spaced away from, the longitudinal axis of the cylinder portions, the merging portions of said walls defining a communication always open to both cylinder portions, a header disposed between said walls having a passage through which fluid under pressure is adapted to 15 be supplied to and released from said communication and thereby said cylinders.
7. A unitary cylinder casing comprising two longitudinally spaced axially aligned cylinder portions having two integral annular walls which extend inwardly toward the longitudinal axis of the cylinder portions and which converge toward each other and merge together about, but spaced away from, the longitudinal axis of the cylinder portions, a header integrally connected to said walls and having a passage through which fluid under pressure is adapted to be supplied to and released from said communication.
